UNITED STATES PATENT OFFICE.

FRIEDRICH WILHELM GUSTAV BRUHN, OF BERLIN-WILMERSDORF, GERMANY.

RECORDING APPARATUS.

Application filed September 2, 1921. Serial No. 497,967.

To all whom it may concern:

Be it known that I, FRIEDRICH WILHELM GUSTAV BRUHN, residing at Berlin-Wilmersdorf, Nassauischestr. 64, Germany, have invented certain new and useful Improvements in Recording Apparatus, of which the following is a specification.

My invention has for its object primarily recording apparatus designed to be employed for the supervision of the running times, speeds and nature of operation existing for the time being of vehicles of any description, also of railway vehicles, operative machines, and other devices, which are to be kept under suitable control and observation. To this effect, a counting mechanism indicating the total number of revolutions, or kilometers, or other distance units is driven by one part of the machine to be observed, e. g. by a wheel, whereas on the other hand a marking mechanism or scribe is set in motion which, on a dial or similar chart moved by a clockwork produces marks which permit of drawing conclusions regarding the nature of operation of the machine or vehicle.

My invention refers more particularly to a novel arrangement of such recording apparatus intended in the first place to permit of an easily recognizable observation of the effectiveness of the marking device and of the operation to be supervised. Moreover the invention comprises the design and arrangement of the means for making the observations. It also comprises further the particularly advantageous design of the other parts of the apparatus in such manner as to permit of an exceedingly appropriate and simple arrangement of the various parts of the controlling device. Finally, my invention contemplates the special design of the general arrangement with a view to an easy readability of the markings and of the counting mechanism, as also the reliability and simplicity of operation, and the particular conditions under which the machine may be operating at the time.

With these and other objects in view, the invention will be hereinafter more particularly described with reference to the accompanying drawings, forming part of this specification in which similar characters of reference indicate corresponding parts in all the different views, and will then be pointed out in the claims at the end of the description.

The apparatus shown on the accompanying drawings by way of example represents a recording apparatus such as used more particularly for vehicles, either horse-drawn or power-driven, Figure 1 being a front elevation of the apparatus.

Figure 2 is a vertical sectional view, taken close above the recording dial or chart.

Figure 3 represents a side elevation of the interior the casing being shown in vertical section.

Figure 4 is a bottom plan of that portion of the apparatus containing the marking and counting mechanism.

Fig. 4^a represents a perspective view of the device for imparting the movement of the driving shaft to the marking and counting mechanism.

Figure 5, represents a vertical sectional view, one part of which is taken below the lower front plate of the clockwork, the other part being taken above the rear part of the same clockwork.

Figure 6, shows a detail in enlarged scale.

The entire arrangement is contained in a flat cylindrical casing 1 which is closed by a cover 2 provided with a window 3. The cover is fastened to the casing by means of a hinge 4 and is locked at the opposite side by means of a bolt or similar locking device which may be sealed in a suitable manner. The casing contains two works, the lower one of which serves for operating the two marking devices and the counting device, whereas the upper one serves for the transport of the recording dial or chart. The lower works, which are illustrated more particularly in the Figures 2 and 5 in front elevation, and in the Figures 3 and 4 in side elevation, are arranged between the plates 6 and 7. The lower works are distinguished by an extremely simple construction which permits of arranging the two marking devices within close proximity of each other, thus greatly facilitating the observation.

The upper plate 6 of these works is provided with an aperture 8 for the driving ratchet wheel 9, an arced aperture 10 for the main marking device which, in the present case is designed as a punch, and a small circular aperture 12 admitting an additional punch having a blunt head or beating pin 13 which is set in motion by the vibrations imparted to the device. Fig. 6 shows the beating head 13' of the pin 13.

As illustrated in Fig. 1, the marks of the

punch 11 serving as main marking device and perforating the chart 14 from the rear, appear in the known manner in the shape of zig-zag curves, whereas the pin 13 acts in such manner on the recording chart, that the latter becomes embossed, and the marks appear on the outer rim of the chart where they form themselves in a circle-segment for the period during which the recording device is exposed to vibrations.

The recording chart 14 is held against the perforating movement taking place from the rear to the front, by a horn 16 one side of which comes up close to the perforations without, however, covering them over, so that as Fig. 1 shows, the markings are clearly visible from the very moment they are produced. The horn 16 is held to the upper plate 6 by means of a support 17 (Fig. 4) in such a manner that it is pressed upward automatically under the influence of a spring 18 whenever the cover of the casing is opened. Only when the cover is pressed down, the spring 18 is depressed, the horn 16 being thus brought correspondingly nearer to the recording chart.

The upper plate 6 has inserted in it the counting mechanism 19, the numbers of which appear inside a correspondingly large sector of the recording dial 14 (cf. Figs. 1 and 2). This arrangement permits of placing also the counting mechanism inside the casing and avoiding the transparent recording charts and pressing-down arrangement hitherto used.

Into the casing 1 a rotating spindle 20 is introduced from below, this spindle being connected to a flexible driving shaft through the intermediary of which it is set in motion from one of the wheels of the vehicle. Inside the casing the spindle 20 is fitted with an eccentric 21 (Figs. 4, 4^a and 5) which turns within a forked lever 22. This lever turns on a shaft 23 and is rigidly connected to a lever arm 24, the latter carrying a ratchet feeding pawl 27 which is pivoted on the spindle 25. This pawl engages under the influence of a spring 26 the teeth of the ratchet wheel 9 which, on the other hand, is also under the influence of a retaining pawl 28. When the forked lever 22 is moved up and down by the spindle 20 and eccentric 21, the pawl 27, which is pivotally mounted on lever 22 in a transverse vertical plane through pivot point 23, follows the rocking motion of the lever. Since pawl 27 is pivoted as shown, so that it swings itself in a plane at right angles to the operating plane of lever 22, in order to enable it to be pressed into engagement with ratchet wheel 9 by means of spring 26, this pawl will feed the ratchet wheel step by step in clockwise direction (see Fig. 4^a) when lever 22 is rocked by eccentric 21. The ratchet wheel 9 may easily be taken off its shaft 30 on

which it is fastened, by loosening two small screws 29 (cf. Fig. 2). The shaft 30 is rotatably supported in a plate 31 and in the lower plate 7 and carries a worm 32 and a cog wheel 33 the teeth of which run in axial direction and are faced obliquely only on one side. Into the worm engages a gear wheel 34 which is fastened on the shaft 35 mounted rotatably below the upper plate 6. This shaft carries a second gear wheel 36 which, in a manner not represented on the drawing engages rearwardly in the first driving wheel of the counting mechanism 19. Finally, a cylinder 37 is fastened upon the shaft 35, the end surface of which is faced off obliquely. Against this oblique surface a roller 38 presses, this roller being fixed to a bell crank 40 supported on a shaft 39 between the two plates of the works. The other end of this bell crank contains the punch or needle 11 which passes through the slot 10 of the plate 6 and owing to the cooperation of elements 37, 38 describes the previously mentioned curved reciprocating movement corresponding to the marks on the recording chart 14. The coupling of the driving worm with the counting mechanism and the curved guide for the main marking member 11 by means of the shaft 35 is of particular value for the simplification of the entire operating mechanism and permits of placing the two marking devices directly adjacent to each other for effecting the marks on the recording chart.

A cam 41 acts in conjunction with the cog wheel 33 fixed upon the spindle 30, this cam being fastened to a plate 42 (cf. Figs. 4 and 5). This plate is rotatably mounted on a pivot 45 in two projections 44 of the lower plate 7 and is under the influence of a leaf spring 46 which tends to hold the plate in the center position as represented on the drawing. When the worm wheel 32 turns in the direction of the arrow, the cam 41 and, with it the plate 42 are pressed downward thus putting the spring 46 under tension. However, whenever the cam tilts over one of the cogs of the wheel, it drops into the next gap between the teeth, the plate 42 hitting the free end of the perforating lever 40 with a strong blow thus forcing the punch 11 through the registration chart.

The easily removable fixture of the ratchet wheel 9 has the advantage that the recording apparatus may be very conveniently adjusted to the diameter of the driving road wheel by simply exchanging the readily accessible ratchet wheel. The aperture 8 in the upper plate 6 is made so large that ratchet wheels for all customary sizes of road wheels may be fitted.

The beating mechanism 13 set in motion by vibrations of the entire registering apparatus, is arranged at the end of the shorter arm of the bell crank 47, the latter being

rotatably mounted on a spindle 48 and being provided at its other longer arm with a weight 49 (Figs. 3-5). Ordinarily, a spring 50 pulls back the pin 13 in opposition to the action of the weight 49. But whenever the apparatus is exposed to vibrations, the lever 47 swings like a pendulum round its pivot and the pin 13 produces marks as illustrated on the outer rim 15 of the recording chart or other marks of similar effect. These marks are quite independent of the record of the main marking device and, in the example illustrated in Fig. 1, convey the information that the car has been run uninterruptedly from 10 a. m. till 12.30 p. m. and then intermittently up to 6.30 p. m., and further in the evening from 8.15 till 9.30 p. m., and again from 11.45 p. m. till 2 o'clock in the morning, without the main marking device having made any record at all; it may, therefore, be concluded that the drive of the main marking device has in some manner been put out of action during the last two periods. This vibratory marking device may also be made so sensitive that it responds even to the vibrations of the engine of a motor car running idle whereby it is possible to obtain a record on the recording chart of the time during which the engine is running while the car is standing.

The clockworks 51 serving for the transport of the registration chart 14, is held between two plates 52, 53 (cf. Figs. 2 and 3). The upper plate 52 carries another plate 54 over which the interior aperture of the recording dial 14 fits exactly. Two projections or lips 55 of this plate (cf. Fig. 1) provide a support for the front of the recording chart so that it cannot slip off. The clockwork 55 drives by means of an exterior toothed rim 56 and through the intermediary of a train of gear wheels not represented on the drawing, its balance 57. Its winding ratchet wheel 59 located at the lower surface and working in conjunction with the ratchet pawl 58, is fitted with a lever 61 (Fig. 5) which is kept under tension by a spring 60. When the clockwork is wound up by means of a key placed over the square winding arbor 62 (cf. Fig. 5), the lever 61 will first strike against a stop 63 whereby its spring is put under tension. During the further rotation of the ratchet wheel 59, the lever slips off this stop and strikes against a bell crank 65 rotatably mounted upon a spindle 64, whose other, resilient arm moves past the outer rim of the balance 57 in the manner indicated by the dotted arrow, thus carrying the latter along with it. In this manner the clock movement is started automatically during the winding-up operation and a stoppage of the clock is thereby prevented.

The upper portion of the clock movement

is provided with two toothed rims 66 and 67 engaging a pinion 68 which serves for the transport of the recording chart 14 (Fig. 2). This pinion is mounted in the plate 52 slidingly on a pivot 69 and is provided with a hub 70 which is provided with an annular groove 71. Into this groove engages a forked lever 72, the opposite end of which is guided by means of a pivot 73 in a slot of the plate 52 and is connected to a head 75 protruding beyond the slot. The lever 72 is provided with two catches 76 into which engages a resilient counter lever 77. A spring 78 keeps the forked end of the lever in engagement with the groove 71. Depending upon whether the knob 75 is moved in one or other direction, the pinion 68 is made to engage either with the outer rim 66 of the clockwork or with the inner toothed rim 67. Accordingly the wheel 68 will be made to turn at different velocities, the dimensions being made such, in respect of the center of the recording chart 14, that the latter when driven from the toothed rim 66, moves at double the circumferential speed of that imparted by the toothed rim 67.

In the example illustrated on the drawing the recording chart is transported by the interior toothed rim 67 and, corresponding to the numbers signifying hours printed thereon, makes one revolution per day. When the driving pinion is shifted toward the interior by means of the knob 75, the circumferential speed is doubled and it is possible to use a recording chart for 12 hours. With due consideration for the corresponding time units, also the same recording dial may be used.

A check as to which of the two speeds has been used during the recording is possible by the pinion 68 also producing a mark during its operation, this mark being made near the inner or outer edge of an interior annular strip 79 of the recording chart. The punctuation indicated on the interior side of the annular surface would mean that the same recording dial has also been run for a certain period at double the speed which would indicate a double utilization of the recording dial.

In order to provide for an effective coupling of the recording dial 14 with the driving pinion 68 and, at the same time for producing the marks previously mentioned, the abutment shown in Figs. 1 and 3 has been provided. This consists of a lever 80 mounted rotatably within the plate 54, the short interior end of which is acted upon by a spring 81 in such a manner that this spring tends to retain this lever in the depressed position as represented, or else in an upturned position forward. A cylinder 82 is rotatably supported on a spindle 83 within an aperture 82 of the lever 80. This cylinder is provided with two slots 84, 85, one or

another of which, according to the position of the driving pinion 68 registers with the latter thus pressing the recording chart down upon the teeth of the pinion. Notwithstanding the pressure of the cylinder 82' being comparatively light, the coupling of the recording chart with the driving pinion is absolutely positive and secure.

Having thus described my invention, I claim as new and desire to secure by Letters Patent:—

1. In recording apparatus of the type described the combination of a clockwork, a recording chart which is driven by said clockwork, a driving gear operated by the object to be observed, a marking device driven by said driving gear and working from the rear against the recording chart in a direction at right angles thereto, and another marking device set in motion by the vibrations imparted to the apparatus by the object to be observed also working from the rear against the recording chart in a direction at right angles thereto, the markings of both marking devices being visible on the face of the chart.

2. In recording apparatus of the type described the combination of a clockwork, a recording chart which is driven by said clockwork, a marking pricker working from the rear against the recording chart, a driving gear operated by the object to be observed setting in motion said marking pricker, a bell crank lever influenced by a weight, a bearing support for said lever, a spring influencing said lever, and a hammer-like punch fixed to said lever working from the rear against the recording chart in a direction at right angles thereto, the markings of the pricker and of the punch being visible on the face of the chart.

3. In recording apparatus of the type described the combination of a clockwork, a recording chart which is driven by said clockwork, a marking device working from the rear against the recording chart in a direction at right angles thereto, a driving gear operating said marking device and driven by the object to be observed, another marking device set in motion by the vibrations imparted to the apparatus by the object to be observed working from the rear against the recording chart in a direction at right angles thereto, and an abutment for the recording chart arranged to one side adjacent to both the marking devices, the markings of both the marking devices being visible on the face of the chart from the moment of their origin.

4. In recording apparatus of the type described, in a casing the combination of a clockwork, a recording chart driven by said clockwork, a marking device, a counting mechanism, a driving member operated by the object to be observed, another marking

device set in motion by the vibrations imparted to the apparatus by the object to be observed, both the marking devices working in a direction from the rear against the recording chart at right angles thereto in such manner that the markings are visible on the face of the chart, two plates connected together and forming a support for the marking devices and the counting mechanism, a ratchet wheel set in motion by the driving member and arranged within an aperture in the front plate of said plates through which it may easily be exchanged, a worm drive actuated from the ratchet wheel, a shaft coupled to the worm drive, a driving pinion for the counting mechanism mounted on the shaft, and a curved driving member for operating the first said marking device also mounted on said shaft.

5. In recording apparatus of the type described, the combination of a clockwork, an annular recording dial or chart moved by said clockwork, a main marking arrangement operating upon the said chart, a counting mechanism, and a driving arrangement moved by the object to be observed and simultaneously driving the marking and counting devices, with a marking device which is only operated by the vibrations imparted to the recording apparatus, a marking member attached to the said marking device, a bearing arrangement for the marking member designed to permit of the latter acting upon the outer rim of the recording chart adjacent to the marks of the main marking device, different driving gears of the clockwork, and a driving pinion for the recording chart, this pinion being made slidable so that it may be made to engage with the different driving gears whereby, according to its adjustment, the driving pinion produces different marks on the recording chart.

6. In recording apparatus of the type described, the combination of a clockwork, an annular recording dial or chart moved by the said clockwork, a main marking arrangement operating upon the said chart, a counting mechanism, and a driving arrangement moved by the object to be observed and simultaneously driving the marking and counting devices, with a marking device which is only operated by vibrations imparted to the recording apparatus, a bearing arrangement for the said marking member designed to permit of the latter acting upon the rim of the recording chart adjacent to the marks of the main marking device, an aperture in the center of said chart, different driving gears of the clockwork and a driving pinion for said chart, this pinion being made slidable in order that it may be caused to engage with the different driving gears whereby, according to its adjustment, the driving pinion produces

different marks on the chart near the interior aperture of same, a lever located inside the aperture of the chart, this lever being made so that it may turn up or down and press the recording chart down upon the driving pinion.

7. In recording apparatus of the type described, the combination of a clockwork, an annular recording dial or chart moved by the said clockwork, a main marking arrangement operating upon the said chart, a counting mechanism, and a driving arrangement moved by the object to be observed and simultaneously driving the marking and counting devices, with a marking device which is only operated by the vibrations imparted to the recording apparatus, different driving gears of the clockwork and a

driving pinion for the recording chart, this pinion being made slideable so that it may be caused to engage with the different driving gears whereby, according to its adjustment, the driving pinion produces different marks on the chart near the interior aperture of same, a lever, a spring acting upon this lever, and a second resilient lever which during the winding up of the clockwork, is set in motion by the first lever thus starting the balance of the clockwork to move.

In testimony whereof I affix my signature in presence of two witnesses.

FRIEDRICH WILHELM GUSTAV BRUHN.
